(57) **CLAIM**

The ornamental design for an insole, as shown and described.

DESCRIPTION

FIG. 1 is a front and bottom perspective view of an insole, showing our new design;

FIG. 2 is a rear and top perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged perspective view of detail "9" identified in FIG. 2;

FIG. 10 is an enlarged perspective view of detail "10" identified in FIG. 2;

FIG. 11 is an enlarged elevation view of detail "11" identified in FIG. 5;

FIG. 12 is an enlarged elevation view of detail "12" identified in FIG. 6;

FIG. 13 is an enlarged top plan view of detail "13" identified in FIG. 7; and,

FIG. 14 is an enlarged bottom plan view of detail "14" identified in FIG. 8.

The dashed lines in the figures illustrate portions of the insole that form no part of the claimed design. The dash dot dash lines are for the purpose of illustrating the enlarged views indicators and form no part of the claimed design.

1 Claim, 14 Drawing Sheets
